HENRI PÉQUIGNET, OF MONTREUIL, FRANCE.

INTERNAL-COMBUSTION ENGINE.

1,408,775.

Specification of Letters Patent. Patented Mar. 7, 1922.

Application filed March 6, 1919. Serial No. 281,020.

To all whom it may concern:

Be it known that I, HENRI PÉQUIGNET, a citizen of the Republic of France, residing in Montreuil, Seine, France, have invented certain new and useful Improvements in Internal-Combustion Engines, of which the following is a specification.

The present invention has for its object to provide an improved distributing system for all kinds of four stroke internal combustion engines, which permits the reduction in a great measure of the number of distributing parts, and also eliminates shocks that are common to valved arrangements.

15 The improved distribution is characterized chiefly by the arrangement of a cam mounted directly on the engine shaft and formed so that its working surface is only traversed once in two revolutions, being thereby adapted to control periods that occur in every two revolutions as is required in motors of the four stroke cycle type. The distribution is also characterized by a 20 valve system specially designed to co-operate with the cam and assure a functioning under satisfactory conditions.

30 The following description with reference to the accompanying drawing, given by way of example, relates to a practical mode of carrying out the invention and explains the characteristics and advantages thereof.

Fig. 1 shows a view from one side of a motor having the invention applied, the upper part being a section through the axis of 35 the controlling valve and the lower part a section along the axis of the cylinder.

Fig. 2 is a plan view, which is at right angles to the view of Fig. 1, showing only parts of the distributing system.

40 In the Figs., the engine shaft is represented by *a*, the distributing cam, keyed directly to the shaft is denoted by *b*. The cam is adapted to act through a controlling rod *c* on the distributing valve *d* which is of 45 cylindrical type and is reacted on by a spring *e*.

The profile of the cam is designed especially to ensure the admission and exhaust at the proper times with the valve as shown; 50 but it is evident that it can be employed for any other purpose. In the present case the admission inlet port is at *f*, whilst the exhaust port is situated in the upper part at *g*. Between the two ports is an opening *h* which 55 affords communication between the valve

box and the interior of the cylinder, and serves alternately for the admission and exhaust. With such an arrangement, when the valve is pushed toward the top to a position as indicated in the Figs., the cylinder becomes open to the exhaust and when the valve descends towards the bottom the cylinder becomes open to the admission.

It is easy to understand, under these conditions, how the profile of the cam serves 65 to control the distribution. The cam comprises two peripheral paths *b'*, *b²*, each of which extends through 360°. These paths follow on each other and do not give rise to any break in the continuity; the path *b'* 70 after one turn through 360° arrives at the upper part of path *b²*, which terminates after one turn at the upper part of *b'*, taken as the starting point. Under these conditions, the piece or shoe *i* mounted on the lower end of 75 the valve rod *c* will produce the following movements when the cam turns in the direction of the arrow *F*.

While the cam turns through 180° the valve will remain in the upper position, lying within the lines *X X* and corresponding largely to the exhaust period; then as the piece or shoe *i* descends along the inclined part *k*, *k'* it will cause the valve to pass to its lower position between the lines *Y Y*, 85 when the admission period commences. After turning through a second 180° about, the piece *i* arrives on the ramp *k²*, *k³* causing the valve to move to its mid-position where the admission and exhaust ports are closed. 90 This mid position is retained during about the subsequent 360°, of the path, that is, from *k³* to *k⁴*, during which compression and expansion takes place. In this way after two complete revolutions one entire cycle of 95 operations of the motor will have occurred and the valve will recommence to rise for the exhaust, starting at *k⁴*.

The device for controlling the valve is arranged to adapt itself to the cam which 100 operates it. It comprises a gudgeon *l*, to which is articulated the head of the rod *c* which consists of a number of parts connected together. The chief part is swivelled at the middle of the rod at *m*, and comprises 105 a cylindrical projection that engages in a corresponding socket and permits the rotation of the lower part about its axis. A second part serves to connect the piece *i* to the control rod, being constituted by a joint 110

n whose axis is parallel to the direction of the contacting piece or shoe *i*.

The shoe *i* is itself directed by the path *b'*, *b²* of the cam in which it is seated with the requisite small play, it is moreover rounded at its ends to facilitate its sliding. Owing to this mode of mounting, it will be seen that when the shoe *i* arrives at the deviating parts *p* and *p'* of the peripheral path, rotation of the lower portion of rod *c* is produced, but without affecting the valve by reason of the swivel *m*; on the other hand, the inclinations of rod *c* which result from the lateral displacement of the shoe *i* do not tend to jam the latter by reason of the action of joint *n*.

Means are also provided to facilitate the passage or movement of shoe *i* at the crossing point of the two paths of the cam. This crossing, which occurs at the parts *p* and *p'* is effected by an opening *g*, provided in the wall of the path in the upper part *p*, which allows the passage of the rod when the shoe *i* comes to the part *p'*; moreover, for the purpose of reducing to a minimum the interruption of the cam at the part *p*, the foot of the valve rod is flattened at *r* in the direction of its width, so that the opening *g* has only a restricted width with respect to the dimensions of the shoe *i*.

By means of the described arrangement the crossings are negotiated with all the desired facility, at the greatest speed of the engine.

Means are provided for lubricating the valve, which is effected in the following manner. The oil circulates under pressure in the tube *t* and traverses the hollow pipe of the piston, thus cooling this pipe. The oil also lubricates the lower part of the cylinder, in which the piston is displaced, and by splashing, it equally lubricates the roller or slide *i*. The lubrication of the upper part of the valve is made by several pipes *v*, one of which is shown in section at the upper part of Fig. 1. A drop of oil is aspirated by each of these channels *v* at each descending stroke of the piston valve, on account of the depression which occurs in the upper part of the cylinder in which the valve is displaced by the lowering of the said piston. This depression can be regulated by modifying the play which exists between the tube *z* and the tube *w* in which the tube *z* slides. The less play that exists between these tubes, the stronger will be the aspiration at the upper part of the cylinder of distribution, and the greater will be the quantity of oil aspirated by the tubes *v*.

In this way a proper lubrication of all parts of the mechanism is attained.

It is to be understood that the above arrangements are in no way limited, for while keeping within the scope of the invention, to the distributing system may be applied any modifications in respect to details, and

dimensions to suit different cases. Cams such as above described may be employed in any other mechanical system for which they may be appropriate.

Having thus described the nature of the 70 said invention and the best means I know of carrying the same into practical effect, I claim:—

1. In a four cycle internal combustion engine the combination with a valve, a cam and 75 an intervening connection for communicating motion from the cam to the valve, said cam having a continuous working face lying mainly in two planes with portions crossing between and comprising two complete circuits each extending through 360° and its working face partly concentric in arcs corresponding to the periods of rest of the valve, and partly varying in radial dimensions to impart movement to the valve, and said valve 80 of the balanced type, to relieve the cam and connection of stresses due to pressure.

2. In a four cycle internal combustion engine the combination with a valve, a cam and 90 an intervening connection for communicating motion from the cam to the valve, said cam having a continuous working face lying mainly in two planes with portions crossing between and comprising two complete circuits each extending through 360° and its working face varying in radial dimensions to impart movement to said connection, and 95 comprising concentric portions of different radii corresponding respectively to the admission, compression and power, and exhaust 100 strokes, and inclined portions connecting such concentric portions.

3. In a four cycle internal combustion engine the combination with a valve, a cam and 105 an intervening connection rod for communicating motion from the cam to the valve, said cam having a continuous working face lying mainly in two planes with portions crossing between, the one over the other, the upper portion of the cam at the point of 110 crossing having a gap for the passage of such rod, and comprising two complete circuits each extending through 360° and its working face comprising alternated concentric and inclined portions, the concentric 115 portions of different radii corresponding to the positions of rest of the valve.

4. In a four cycle internal combustion engine the combination with a valve, a cam and 120 an intervening connection for communicating motion from the cam to the valve, said cam having a continuous working face lying mainly in two planes with portions crossing between, and comprising two complete 125 circuits each extending through 360°, and its working face varying in radial dimensions to impart movement to said connection, and having concentric portions of three different radial dimensions to cause the valve to dwell in position for the admis- 130

sion, the compression and power strokes, and the exhaust and said intervening connection comprising a shoe bearing on the working surface of said cam to receive the movement 5 imparted by said cam.

5. An engine according to claim 3, the connection rod formed in two parts rotatably connected, one end of the first part pivotally

connected to the valve and a shoe connected to the opposite end of the second part, and 10 the latter flattened where it passes through the gap of the cam.

In witness whereof, I have hereunto signed my name.

HENRI PÉQUIGNET.
